UNITED STATES PATENT OFFICE.

FREDERICK H. MEIER, OF SHEFFIELD, ILLINOIS.

SEGMENTAL CLAY-BLOCK STRUCTURE.

Application filed May 21, 1927. Serial No. 193,188.

The object of my invention is to provide a segmental clay block structure of simple, durable and efficient construction adapted for use for sewers and drains, walls, hollow tile blocks and the like.

A particular object of my present invention is to provide a sectional clay block structure comprising sections adapted to be assembled and put together on the job for making a tile, culvert, wall or the like.

It is my particular purpose to provide sections in such a structure having coacting inter-engaging members for making a joint of great strength.

Another object is to provide such sections constructed and arranged for conveniently making joints of great strength between adjacent tile or wall portions.

In this connection, it is my object to provide sections preferably formed with inner and outer walls having air spaces between them and with suitable transverse connecting members, which sections are provided at their coacting adjacent side edges with parts adapted to inter-engage and provide means, whereby a locking post of concrete or other material may be received for making strong, tight joints.

Another purpose is to provide such sections peculiarly arranged for connecting the ends of one tile or block or the ends of a series of sections with the ends of another tile or block or series of sections.

With these and other objects in view, my invention consists in the construction, arrangement and combination of the various parts of my segmental clay block structure, whereby the objects contemplated are attained, as hereinafter more fully set forth, pointed out in my claims, and illustrated in the accompanying drawings, in which:

Figure 1 is a perspective view of a segmental clay block structure made in the form of a tile, parts being broken away and parts being shown in section.

Figure 2 is a detail, sectional view taken on the line 2-2 of Figure 1, illustrating the arrangement of two tile placed end to end.

Figure 3 is a detail, sectional view taken on the line 3-3 of Figure 2.

Figure 4 is a perspective view of two sections of the kind used in forming the upper half of a tile.

Figure 5 is a similar view of two sections of the kind used for forming a lower half of a tile.

Figure 6 is a perspective view of one of the locking plates used in connecting together the ends of two tile at the upper half thereof.

Figure 7 is a similar view of the locking plate used for connecting together the ends of two tile at the lower half thereof.

Figure 8 is an end view of a portion of one tile comprising a segmental block structure embodying my invention.

Figure 9 is a detail, sectional view taken on the line 9-9 of Figure 1; and

Figure 10 is a detail, sectional view taken on the line 10-10 of Figure 9.

Clay is economical material for manufacturing a great many structures. Its use involves, however, certain problems due to the difficulties of transporting large blocks and particularly large tile from the factory to the place of installation.

The benefit of using the clay may be had and substantial economies can be effected, if the product can be used in the form of sectional blocks adapted to be assembled together into walls, completed tile or the like on the job. Such sections must be built in such manner that when connected together, they will make a strong structure with tight joints.

Where large tile are used the use of sections is advantageous because the sections can be assembled on the job without the necessity for handling the very heavy complete tile.

Another problem that arises in connection with large clay tile is that of connecting together the ends of successive tile in a sewer or the like for fastening the tile together and making a tight joint.

All of these problems I have sought to solve by the structure herein to be described.

I provide a series of blocks or sections peculiarly adapted to be connected together in a

curved wall or in hollow blocks or in the form of ordinary tile.

In Figure 1, I have shown some of my sections assembled together in a complete tile.

5 In Figures 4 and 5 I have shown some of the sections.

All of the sections are formed with an outer wall 10 and an inner wall 11, spaced from each other and connected together by radial connecting walls 12.

The walls 10 and 11 may be curved on the arc of a circle having its center at the center of a contemplated complete tile.

In each section as it comes from the die in 15 the clay works, the walls 10 and 11 are connected together at the side edges of the section by means of walls 14 and 15, inclined toward each other, as shown for instance in Figures 4 and 5, and connected by a short radial cross wall 16.

The outer and inner faces of the respective walls 14 and 15 are inset from the outer and inner faces respectively of the walls 10 and 12.

25 The angles of the inner face 14^a and the outer face 15^a of the walls 14 and 15 are so arranged with relation to the angles of the outer and inner faces of the said walls respectively that said walls are thicker adjacent to the walls 16 than adjacent to the walls 10 and 11.

These faces 14^a and 15^a are inclined from the adjacent cross wall 12 as shown in Figures 4 and 10 for instance, so as to leave between the walls 12, 14, 16 and 15 a longitudinal passage 20 (see Figure 1).

It will therefore be observed that in the completed structure of each section, there is provided at each side edge a longitudinal hollow extension not so thick as the main body of the section, tapered toward its outer edge or wall 16, said extension being comprised of the walls 14, 15 and 16.

In completing each section, portions of 45 each of such extensions are cut away longitudinally of the section by means of a suitable machine employing cutting wires or the like.

As shown for instance in Figure 4, the portions of the extensions remaining are indicated as at A and the recesses between them formed by cutting away certain parts of them are indicated at B.

55 Thus along the length of each side edge of each section, there is provided a series of projecting extensions A, alternating with a series of recesses B.

In each section, the extension members A at one side edge are staggered with relation 60 to the extensions A at the other side edge (see for instance Figure 5), so that when two sections are placed with their side edges adjacent, the extensions A of one section will fit into the recesses B of the adjacent section. 65 (See Figures 1 and 4.)

In forming sections designed for use in tile or the like, wherever sections are to be connected end to end, portions are cut away at the ends of the sections in the following manner:

70 For instance in those sections which are to be used for the top half of a tile, such as that shown in Figure 1, I cut longitudinally of the section from the end on a line having curvature corresponding to that of the walls 10 and 11 for a substantial distance and then cut radially inwardly, thus forming in the outer face of each section adjacent to each end a rabbet indicated generally in Figure 4 at C. This rabbet extends inwardly from the outer face of the wall 10, less than half of the thickness of the section.

A similar rabbet is cut on the inside of each section designed for the lower half of a completed tile at each end thereof for less than half the thickness of the section. This rabbet is indicated at D in Figure 5.

80 Sections of this kind may be used for curving walls, may be made with the curvature for hollow blocks with sectional walls, or may be used for drain tile and the like.

85 For purposes of description, I will refer more particularly to the use of the sections in drain tile.

90 The sections or blocks, such as those shown in Figures 4 and 5 are made at the factory and are shipped to the job and assembled there into the completed tile.

95 In making a tile, the sections for a tile may be set on end and slipped together with the extensions A of each section received in the recesses B of the next adjacent section.

100 The sections are easy to slip together in this way because of the beveled faces of the walls 14 and 15, and because when the portions of the extensions are cut out to form the recesses B, the walls 14 and 15 are cut on lines as indicated by dotted lines at 22 and 24 in Figure 10, inclined from the junction of the faces 14^a and 15^a with the wall 12 to the junctions of the outer and inner faces respectively of the walls 14 and 15 with the walls 10 and 11.

105 When the sections are thus assembled in a tile, there is at the junction of each section with the next section a continuous longitudinal opening 20 extending through the extensions A of the respective adjacent sections. That opening may be filled with any suitable locking means, such for instance as with slush cement, which when hardened will form a longitudinal post 26 in the continuous passage or hole 20, extending lengthwise of the finished tile.

110 It will be noted that this post when formed of concrete does not have a smooth wall lengthwise of the tile because the opening 20 in the extension A of one section does not register exactly with the opening 20 in the 115 120 125 130

next adjacent extension A of the adjacent section. This is illustrated in Figure 10, in which a portion of one of the posts is illustrated in longitudinal section.

It thus follows that the post 26 which fills the holes 20 has portions extending radially beyond the joint lines for thus making a very strong interlocking means for the sections.

It will, of course, be understood that in 10 making a tile, I select enough of the sections of the kind shown in Figure 4 to form the upper half of the completed tile and enough of the sections of the kind shown in Figure 5 to form the lower half thereof.

15 When a series of sections have thus been connected together to make a tile of the kind shown in Figure 3, there is produced a structure of great strength.

I have shown in making tests of my tiles 20 of this kind and of the kind shown in my prior Patent, No. 1,430,094, issued September 26, 1922, that when the tile is placed in horizontal position, substantially as it would be when in the ground, and is then subjected 25 to a load as by imposing a great weight thereon, the tile will first crack along a line, such as that indicated at 28 in Figure 1, extending from the junction of the wall 10 with the cross wall 12.

30 By making the walls 14 and 15 thicker in the manner already described along their lines of connection with the body of the section and cutting the recesses B on the lines 35 22 and 24 (see Figure 10) in the manner already described, I have discovered that the block will have far greater strength as compared with the block in which the faces 26 and 14^a and 15^a might be cut in planes parallel 40 with the outer and inner faces of the section.

I will now describe in greater detail the means for connecting together two successive tile in a drain or sewer.

It will be noted that in the completed tile, 45 as shown in Figure 1, the tile is provided at both ends at its upper half with a rabbet in its outer surface and at both ends of its lower half with rabbets in its inner surface.

I cut sections such as that shown in Figure 4 50 into transverse strips and then cut these midway between the inner and outer walls 10 and 11 for thus forming inner and outer binder strips 30 and 32, such as are shown in Figures 6 and 7.

55 The lower rabbet at the end of the tile is then filled with slush cement and binder strips 32 are then placed in position to fill the rabbet. One of the binder strips 32 may be broken in two between its ends to form 60 a smaller binder strip 32^a, such as is shown in Figure 3, and the joints between the successive binder strips 32 and 32^a at the lower part 65 of the tile are broken with relation to the joints of the sections of the lower half of the tile.

The projecting portions of the walls 12 form fingers 12^a, which project into the slush cement overlapping the fingers 12^b formed by the walls 12 from which the rabbet has been cut.

70 The inner faces of the binder strips 32 complete a smooth inner surface for the tile.

The strips 32 and 30 are wide enough to overlap the joints between the successive tile.

75 The strips 30 are placed in the rabbets at the upper half of the tile in a similar way. The manner in which they overlap the joints between the successive tile is illustrated in Figure 2.

80 Thus the successive tile are locked together when the soft concrete 34 hardens by means of the strips 32 and 30 which serve as anchoring and fastening means and also to provide smooth finishing surfaces.

85 There is thus provided a joint between successive strips which has great strength. The successive tile can be easily placed with their ends snugly abutting and no overlapping of parts of the tile is necessary.

90 A segmental clay block structure of the kind herein described has many features of advantage, some of which have been already referred to.

95 Two of the features wherein my present structure differs from that of my prior patent already mentioned I find in the shape of the walls of the extensions A and in the position of the rabbets D and C and the locking strips 100 30 and 32. The shape of the extensions A facilitates the assembling of the sections together and increases the strength of the completed tile wall or block.

105 It will be readily seen that by various slight changes curved walls could be built with sections of the kind herein explained.

110 It is my purpose to cover by the claims of the patent to be issued upon my present application any modifications in structure and arrangement of parts and adaptation of the sections for different shapes and types of structure, so far as such changes and adaptations may be included within the scope of such claims.

I claim as my invention:

115 1. In a structure of the class described, a plurality of sections of plastic material each having an outer and an inner wall and transverse connecting walls, said sections having rabbets formed at their ends exposing the said connecting walls, and means for connecting together sections placed end to end, comprising binder strips arranged to fit into said rabbets and overlapping the joint between the successive sections, said binder strips having portions extending between the exposed transverse connecting walls of the sections.

120 2. In a structure of the class described, a tubular section comprising a plurality of sections of plastic material, each having inner 125

and outer walls and radial connecting walls, said section having at its ends outer rabbets in its upper half and inner rabbets in its lower half exposing said connecting walls, and binder strips for connecting successive sections together, comprising members curved on the curvature of the tile for reception into the rabbets of tile placed end to end in such

manner as to overlap the joints between the tile, said strips having radially projecting walls overlapping and interlocking with the exposed radial connecting walls of the sections where the rabbets have been cut in the ends thereof. ¹⁰

Des Moines, Iowa, May 13, 1927.
